CATHODE ASSEMBLY

Rudolph O'Larte, Rego Park, N. Y., and Kurt Speck, Palisade Park, N. J., assignors to Jacques Kriesler Manufacturing Corporation, North Bergen, N. J., a corporation of New Jersey

Application January 18, 1944, Serial No. 518,684

9 Claims. (Cl. 250—162)

This invention relates to a cathode assembly for a cathode-ray tube or the like.

One object of the invention is to produce a cathode assembly construction in which provision is made to facilitate the mounting of the cathode in proper position in relation to the electron aperture of the grid.

Another object of the invention is to provide a cathode assembly construction by which the assembly operation for producing cathodes for cathode-ray tubes is greatly facilitated.

Another object of the invention is to provide a cathode assembly construction wherein the cathode may be removably secured in position so that it can be replaced in the event that it is defective.

A further object is to provide an improved cathode unit for a cathode assembly for a cathode-ray tube or the like.

The above and other objects, features, and advantages will be fully understood from the following description, reference being had to the accompanying illustrative drawing.

In the drawing:

Fig. 1 is an enlarged side view, in elevation, of a cathode assembly embodying the present invention;

Fig. 2 is an end view thereof;

Fig. 3 is a sectional view on the line 3—3 of Fig. 2;

Fig. 4 is a sectional view of the cathode and of a part associated therewith;

Fig. 5 is a sectional view of a spacer member provided in the cathode assembly in accordance with the present invention;

Fig. 6 is a perspective view of a holding member forming a part of the cathode assembly;

Fig. 7 is a view similar to Fig. 3, showing a somewhat different arrangement of the parts and showing the spacing member in elevation.

Referring now to the drawing in detail, the cathode assembly 10 which is intended for use in a cathode-ray tube comprises a tubular member 12 formed of sheet metal in two parts 14 and 16 which are fixedly secured to each other in tube-defining relation. As here shown, tube-forming parts 14 and 16 are provided at their longitudinal edges with flanges 18 and 20, respectively, for the full lengths thereof. Said flanges are in abutting relation and are secured to each other by inturned edge portions 22 of flanges 20 which are bent over adjacent portions of flanges 18. Flanges 18 and 20 are provided with lateral extensions having flat abutting portions 24 and 26 complementary semi-cylindrical portions 28 and 30, which define small tubular

parts for mounting the cathode assembly on insulation rods in the electron gun mount in the cathode-ray tube, and flat abutting end portions 32 and 34. The flat abutting portions 24, 26 and 32, 34 are spot welded to each other as indicated by the dots on portions 24 and 32 in Fig. 1.

Tubular member 12 is provided with outwardly pressed peripheral ribs 36 and 38 near the opposite ends thereof, respectively, forming corresponding internal peripheral grooves in said tubular member. A disc 40 is mounted in tubular member 18 at the front end thereof and is provided with a central electron aperture 42. Said disc has a peripheral flange 44 provided with an outwardly pressed rib 46 which is received in the peripheral groove formed by the outwardly pressed rib 36 of tubular member 12. It will be understood that disc 40 is formed in one piece and is secured in position between tubular parts 14 and 16 at the time the latter are assembled and secured to each other. Disc 40 is provided with a circular reinforcing bead 47 pressed from the material of said disc. As shown in Fig. 3, disc 40 is positioned at the front of tubular member 12 with flange 44 of said disc extending toward the front end of said tubular member, while as shown in Fig. 7 the position of said disc is reversed, and from this it will be understood that the construction and relation of tubular member 12 and disc 40 are such as to permit the disc to be positioned either as shown in Fig. 3 or as shown in Fig. 7.

In accordance with the present invention, provision is made for mounting the cathode 48 with the forward or electron-emissive end thereof in proper relation to the electron aperture 42. As here shown, said cathode is of the indirectly heated type and comprises a sheet metal tube 50 in which the usual electric filament or heating element (not shown) is positioned. Said tube 50 is closed at its front end by a cap 52 which carries the electron-emissive material, said cap being fixed to the adjacent end portion of said tube. A circular rigid disc 54 formed of ceramic or other insulation material is secured to tube 50 near the forward end thereof and is held against movement longitudinally of said tube by the lateral projections formed as here shown by a flange 56 provided on cap 52 and by a collar 58 which as shown in Fig. 4 is constituted by an outwardly pressed peripheral rib or bead with which tube 50 is provided. It will be understood that in assembling insulation disc 54 with tube 50 and cap 52, tube 50 is projected through the central circular opening 60 of disc 54 before cap 52 is secured in position and that after said disc is mounted

on said tube, cap 52 is mounted on the forward end portion of said tube and is secured thereto in any suitable way preferably by welding. Disc 54 is provided with a plurality of openings 61 therethrough.

A spacing member 62 is positioned between grid disc 40 and insulation member 54 for predetermineding the position of cathode 48 and more particularly the electron-emissive part 52 thereof in relation to the electron aperture 42 of disc 40. Spacing member 62, which is formed of sheet metal has a forward flat annular part 64, an outer peripheral rim 66 provided with a peripherally continuous flange 68, and an inner peripherally continuous skirt portion 70 defining a central opening 72 in spacing member 62 and surrounding cap 52 of cathode 48 in spaced relation thereto. It will be understood that spacing member 62 and insulation disc 54 are in engagement at the peripheral edges thereof respectively with the inner peripheral surfaces of tubular member 12 whereby the opening 72 of said spacing member is in axial alignment with electron aperture 42 and whereby cathode tube 50 is in axial alignment with said electron aperture.

Provision is made for holding the cathode 48 in position in tubular member 12. For this purpose the holding member 74 is provided. Said holding member is formed of resilient sheet metal and comprises a forward flat annular portion 76 having a peripheral flange 78 and a plurality of resilient arms 80 which extend longitudinally of tubular member 12 in engagement with the inner surface thereof when holding member 74 is positioned therein. Each of said arms 80 is provided with an outwardly pressed transverse rib 82 near the outer end thereof in position to engage tubular member 12 in the internal peripheral groove thereof formed by rib 38. In this connection it will be understood that ribs 82 are located in arms 80 so that when annular part 76 engages the adjacent surface of insulation disc 54, ribs 82 project into the peripheral groove of tubular member 12. When the grid disc 40 is positioned as illustrated in Fig. 7, ribs 82 are positioned at a greater distance from annular part 76 so as to register with the groove of tubular part 12, the distance between annular part 76 and ribs 82 being less when holding member 74 is constructed to be utilized in the cathode assembly arrangement illustrated in Fig. 3. If desired, however, tubular member 12 may be provided with an additional peripheral groove or with circumferentially spaced openings to receive ribs 82 of holding member 74 so that the same holding member can be utilized either in the assembly where the disc 40 is positioned as illustrated in Fig. 3 or in the assembly where disc 40 is positioned as illustrated in Fig. 7.

In the assembly operation for producing the cathode assembly of the present invention, after the tubular member 12 with the grid disc 40 mounted therein is produced, and after the cathode unit 48 comprising the tube 50, its cap 52 and the disc 54 is produced, the spacing member 62 is placed in the tubular member 12 with the annular flat face 64 thereof abutting said disc 40, then the cathode 48 is positioned in the tubular member 12 with insulation disc 54 abutting flange 68 of spacing member 62, and finally the holding member 74 is positioned in tubular member 12 with the annular part 76 of said holding member abutting the adjacent surface of insulation disc 54 at the marginal edge portion thereof and with ribs 82 resiliently engaging said tubular member

12 in the peripheral groove formed by rib 38. It will be understood that in the case of a defective cathode or if for some other reason it is desired to remove a cathode from the assembly, this can be easily accomplished by withdrawing cathode unit 48 from tubular member 12 after first removing holding member 74 from tubular member 12, said holding member being easily removable from said tubular member by pressing arms 80 readily inwardly to disengage the ribs 82 from peripheral groove of the tubular member, thus allowing said holding member to be removed through the adjacent open end of the tubular member 12. The cathode-ray assembly 10 may be mounted in a cathode-ray tube in any suitable way but preferably is incorporated in the electron gun mount which we have shown and described in our application Ser. No. 499,356, filed August 20, 1943.

Thus it is seen that the cathode-ray assembly construction as herein shown and described is well adapted to accomplish the several objects of the present invention. It will be understood, however, that various changes in the details of construction and in the arrangement of parts may be made without departing from the underlying principles of this invention as embodied in the subject matter of the claims.

Having thus described our invention, what we claim and desire to secure by Letters Patent is:

1. In a cathode assembly for a cathode-ray tube, said assembly comprising a tubular member provided with an electron-aperture and a tubular cathode disposed within said tubular member; an insulation disc fixed to said cathode between the opposite ends thereof and slidably fitting in said tubular member, said disc being provided with an opening in which said cathode is mounted for holding said cathode in axial alignment with said aperture of said tubular member, and metallic means disposed at opposite sides of said disc in radially spaced relation to said cathode and engaging said disc and said tubular member for holding said cathode in spaced relation to said aperture axially thereof.

2. In a cathode assembly for a cathode-ray tube, said assembly comprising a tubular member provided with an electron-aperture and a tubular cathode disposed within said tubular member; an insulation member fixed to said cathode between the opposite ends thereof and positioned in said tubular member for holding said cathode in axial alignment with said aperture of said tubular member, and metallic means cooperating with said insulation member for holding said cathode in spaced relation to said aperture axially thereof.

5. In a cathode assembly for a cathode-ray tube, said assembly comprising a tubular member provided with an electron-aperture and a tubular cathode disposed within said tubular member; an insulation member fixed to said cathode between the opposite ends thereof and spaced from said ends, said disc slidably fitting in said tubular member and provided with an opening in which said cathode is mounted for holding said cathode in axial alignment with said aperture of said tubular member, a metallic member disposed between the apertured end of said tubular member and the adjacent side of said insulation disc for spacing said cathode from said aperture axially thereof, said tubular member having an end opening through which said insulation disc with the cath-

6. In a cathode assembly for a cathode-ray tube, said assembly comprising a tubular member provided with an electron-aperture and a tubular cathode disposed within said tubular member; an insulation disc fixed to said cathode between the opposite ends thereof and spaced from said ends, said disc slidably fitting in said tubular member and provided with an opening in which said cathode is mounted for holding said cathode in axial alignment with said aperture of said tubular member, a metallic member disposed between the apertured end of said tubular member and the adjacent side of said insulation disc for spacing said cathode from said aperture axially thereof, said tubular member having an end opening through which said insulation disc with the cath-

ode mounted therein are insertable as a unit into said tubular member, and means positioned at the other side of said disc for holding the latter in position adjacent said spacing member.

4. In a cathode assembly for a cathode-ray tube, said assembly comprising a tubular member provided with an electron-aperture and a cathode disposed within said tubular member; an insulation disc slidably fitting in said tubular member and provided with an opening in which said cathode is mounted for holding said cathode in axial alignment with said aperture of said tubular member, a member disposed between the apertured end of said tubular member and the adjacent side of said insulation disc for spacing said cathode from said aperture axially thereof, said tubular member having an end opening through which said spacing member and said insulation disc with the cathode mounted therein are insertable into said tubular member, and means for holding said disc in position adjacent said spacing member, said last mentioned means comprising a member having a part positioned adjacent said other side of said disc in radially spaced relation to said cathode and parts extending longitudinally of said tubular member toward said open end thereof, and releasable interengaging means on said tubular member and said longitudinally extending parts for releasably securing said disc-holding means in position in said tubular member.

5. In a cathode assembly for a cathode-ray tube, said assembly comprising a tubular member provided with an electron-aperture and a cathode disposed within said tubular member; an insulation disc slidably fitting in said tubular member and provided with an opening in which said cathode is mounted for holding said cathode in axial alignment with said aperture of said tubular member, a member disposed between the apertured end of said tubular member and the adjacent side of said insulation disc for spacing said cathode from said aperture axially thereof, said tubular member having an end opening through which said spacing member and said insulation disc with the cathode mounted therein are insertable into said tubular member, and means for holding said disc in position adjacent said spacing member, said last mentioned means comprising a member having a part positioned adjacent said other side of said disc in radially spaced relation to said cathode and parts extending longitudinally of said tubular member toward said open end thereof, said tubular member having a recessed portion in its inner surface and at least one of said longitudinally extending parts having a lateral projection releasably engageable with said tubular member in said recessed portion for releasably securing said disc-holding means in position in said tubular member.

6. In a cathode assembly for a cathode-ray tube, said assembly comprising a tubular member provided with an electron-aperture and a cathode disposed within said tubular member; an insulation disc slidably fitting in said tubular member and provided with an opening in which said cathode is mounted for holding said cathode in axial alignment with said aperture of said tubular member, a member disposed between the apertured end of said tubular member and the ad-

jacent side of said insulation disc for spacing said cathode from said aperture axially thereof, said tubular member having an end opening through which said spacing member and said insulation disc with the cathode mounted therein are insertable into said tubular member, and means for holding said disc in position adjacent said spacing member, said last mentioned means comprising a member having a part positioned adjacent said other side of said disc in radially spaced relation to said cathode and parts extending longitudinally of said tubular member toward said open end thereof, said tubular member having a recessed portion in its inner surface and at least one of said longitudinally extending parts being formed of spring metal and having a lateral projection releasably engageable with said tubular member in said recessed portion for releasably securing said disc-holding means in position in said tubular member.

7. A cathode assembly for a cathode-ray tube, comprising a tubular member provided with longitudinally spaced peripheral grooves in its inner surface, a disc provided with an electron-aperture positioned in said tubular member and having its peripheral edge positioned in one of said grooves and thereby secured in position in said tubular member, an insulation disc slidably fitting in said tubular member and provided with an opening in which said cathode is mounted for holding said cathode in axial alignment with said aperture of said tubular member, a member disposed between said discs for spacing said cathode from said aperture axially thereof, said tubular member having an end opening through which said spacing member and said insulation disc with the cathode mounted therein are insertable into said tubular member, and means for holding said insulation disc adjacent said spacing member comprising a member having a part positioned adjacent said other side of said disc in radially spaced relation to said cathode and a part extending longitudinally of said tubular member toward said opening thereof, said part being formed of a spring metal and having a lateral projection releasably engageable with said tubular member in another of said peripheral grooves thereof for releasably securing said holding means in position in said tubular member.

8. A cathode unit for a cathode-ray tube comprising a tube open at one end to receive an electric heating element, a cap mounted at the other end of said tube to carry the electron-emissive material of the cathode, said tube and cap having lateral projections, and an insulation member mounted in position on said tube between the opposite ends thereof and held in said position by said lateral projections.

9. A cathode unit for a cathode-ray tube comprising a tube open at one end to receive an electric heating element, a cap mounted at the other end of said tube to carry the electron-emissive material of the cathode, said tube having an outwardly pressed peripheral rib formed therein and said cap having a lateral projection, and an insulation disc mounted on said tube between said rib and projection and thereby secured in position on the tube between the opposite ends thereof.
